RELEASE FOR AUTOMATIC TELEPHONE SYSTEMS

Filed Jan. 13, 1905

2 Sheets-Sheet 2

UNITED STATES PATENT OFFICE.

ALEXANDER E. KEITH, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

RELEASE FOR AUTOMATIC TELEPHONE SYSTEMS.

Application filed January 13, 1905. Serial No. 240,960.

To all whom it may concern:

Be it known that I, ALEXANDER E. KEITH, a citizen of the United States of America, and resident of Chicago, Cook County, Illinois, have invented a certain new and useful Improvement in Releases for Automatic Telephone Systems, of which the following is a specification.

It will be readily understood that my invention relates to that particular type of automatic telephone system in which each subscriber is provided with means for sending electrical impulses over the line to the exchange or central station—that is to say, for causing a make-and-break action in the "line-circuit"—and in which these electrical impulses, corresponding to the number of the called subscriber, are received by a step-by-step automatic switching apparatus adapted to respond to the impulses or make-and-break action, brought about by the subscriber, and to automatically establish connection with the line leading to the called subscriber's station. The particular switch that receives the impulse or impulses corresponding to the first digit of the called number is termed a "first selector", while the switch which then receives the impulses representing the second digit of the called number is termed a "second selector"; and as many "selectors" may be employed—according to the size of the exchange, and the number of digits involved in the highest number—as may be found necessary or desirable. The switch employed for making the final connection directly with the called subscriber's line, and which receives the impulses corresponding to the last two digits of the called number, is termed a "connector". My invention involves an arrangement by which the said "connector" can be employed by the calling subscriber, when the conversation is terminated, for releasing both the "connector" and the second "selector"; and I have also described and claimed a novel arrangement whereby the said second "selector", when thus released, automatically effects a release or restoration of the first "selector". In each case, an additional trunk-line conductor is employed for releasing between switches. Also, in each case, the "release-

circuit" between the switches includes the "private-wiper" and "private bank-contacts" of the "selector" to be released. But for the broader purposes of my invention I do not limit myself to any particular number of switches, or to any particular arrangement for disconnecting the relay bridges during conversation, or to any particular arrangement for releasing in such a bridge-cut-off system.

It is obvious that with an arrangement of this character the system may involve a first and second "selector", or any number of "selectors", together with a "connector", and that no coils, either in series or in bridge, need be left in the circuit at the different "selectors", the talking circuit being free from inductive resistance, either in bridge or in series, between the transmitting and receiving ends of the circuit, with the two exceptions of the "vertical" and "rotary" relays of the "connector", and the "back release-relays" of the "connector", it being obvious that these relays, or some equivalent arrangement, must be left across the talking circuit, the former in order to make it possible for the calling or called subscriber, for example, to release or restore the different switches after the conversation is terminated, and the latter to enable a called subscriber to disconnect a connector connected with his own line, if he so desires.

The nature and advantages of my invention will, however, hereinafter more fully appear.

In the accompanying drawings Fig. 1 is a diagram illustrating the condition of the apparatus during the time the calling subscriber is conversing with the called subscriber, and showing the apparatus at the calling subscriber's station connected, through the medium of a first selector, with a trunk line leading to a second selector, and through the medium of said second selector with a trunk line leading to a connector, the heavy lines indicating the talking circuit, and the other or light lines indicating the auxiliary circuits employed for operating the different switches, and for various other purposes.

Fig. 2 is similar to Fig. 1 with the excep-

tion that it represents a connection in an exchange of a larger capacity than that shown in Fig. 1.

As thus illustrated, A represents the apparatus or equipment at the calling subscriber's station. B represents the first selector at the exchange or central station, and C the second selector at the same place. D represents the connector at the exchange or central station. E represents a second selector having bank contacts which are multiplied with those of the second selector C. It will be understood, of course, that these automatic switches can be arranged at the same station, or at different stations.

At the subscriber's station A the switch a^1 is employed for grounding first one side and then the other of the subscriber's line, so as to produce the electrical impulses corresponding to the number called. As will hereinafter more fully appear, the switch a^1 is used by the subscriber for grounding both sides of the line, so as to release or restore the switches after the conversation is terminated. The telephone set, comprising the transmitter a^2 and the receiver a^3 , may be of any suitable, known or approved character.

As shown, the subscriber's line 1 has connection with the wipers b and b^1 of the so-called side switch of the first selector B. This first selector may comprise the usual vertical and rotary relays b^2 and b^3 , the private magnet b^4 , the release magnet b^5 , and may also comprise the release relay b^6 described in my said former application. Other familiar features of a first selector of this character consist of the private wiper b^7 of the said side switch, and the private, vertical and rotary wipers b^8 , b^9 and b^{10} on the switch shaft, together with the private, vertical and rotary bank contacts b^{11} , b^{12} and b^{13} .

The second selector C comprises the usual vertical and rotary relays c and c^1 , the private magnet c^2 and the release magnet c^3 . The release relay c^4 is a new feature in a second selector of this character, as is also the resistance coil c^5 . There are also certain novel features in this second selector, as will hereinafter more fully appear; but other familiar elements of a switch of this character consist of the vertical and rotary wipers c^6 and c^7 of the side switch, and the private, vertical and rotary wipers c^8 , c^9 and c^{10} on the rotary switch shaft. The private, vertical and rotary bank contacts c^{11} , c^{12} and c^{13} are also included, as usual, in the construction of the said second selector.

The connector may include the usual back-release relays d and d^1 , the vertical and rotary relays d^2 and d^3 , the private magnet d^4 and the release magnet d^5 . The resistance coil d^6 , described in my former application, is also a feature of the said connector,

which latter is further identified by the private, vertical and rotary wipers d^7 , d^8 and d^9 of the side switch. Other familiar elements in a connector of this character consists of the condensers d^{10} and d^{11} , arranged in opposite sides of the talking circuit between the vertical and rotary relays and the back-release relays. Like other connectors of this character, the rotary switch shaft is provided with private, vertical and rotary wipers d^{12} , d^{13} and d^{14} , and with the corresponding private, vertical and rotary bank contacts d^{15} , d^{16} and d^{17} .

At the other second selector E the private, vertical and rotary bank contacts e , e^1 and e^2 are multiplied, as shown, with the private, vertical and rotary bank contacts, respectively, of the second selector C. Only the release relay e^3 , the private magnet e^4 and the private wiper e^5 of the side switch are shown at the point where the said second selector E is supposed to be located, together with the private, vertical and rotary wipers e^6 , e^7 and e^8 of the rotary switch shaft.

Between the first and second selectors the connection consists of the main trunk line conductors 2 and 2, and of the third or additional trunk line conductor 3. In a similar way the connection between the second selector and the connector consists of the main trunk line conductors 4 and 4, and the third or additional trunk line conductor 6.

Thus, between the first and second selectors there are three trunk line conductors, two to be used for talking, switching and signaling purposes, and the third to be used for releasing purposes after the conversation is terminated. And in like manner, there are three trunk line conductors between the second selector and the connector, two to be used for talking, switching and signaling purposes, and the third to be employed only for releasing purposes after the conversation is terminated.

As illustrated, the apparatus is in the condition necessary for talking purposes, and, assuming the conversation to have been terminated, the calling subscriber may then release or restore the different switches in the following manner: The switch a^1 is first operated at the calling subscriber's station, so as to simultaneously ground both sides of the line and connect the two sides together. This, of course, will result in energizing the vertical and rotary relays d^2 and d^3 at the connector D. It will also result in the energizing of the private magnet d^4 , the circuit of this magnet having been closed by the energizing of the relay d^3 . The relay d^2 and the private magnet d^4 , when energized, effect the closing of a circuit including the release magnet d^5 . It will be seen that all of these energizing circuits, when thus closed, include the battery F and the bus bar or common connection f with which one

pole of the battery is connected, and also include the ground or common connection f^1 with which the other pole of the battery is connected. The release magnet d^3 , when energized, closes the switch d^{18} , and thus closes a ground circuit including the said battery, the resistance coil d^6 , the private wiper c^8 and the private bank contact c^{11} , together with the trunk line conductor 6, the release relay c^4 and the private wiper c^{14} . The release relay c^4 of the second selector C being thus energized, a circuit is thereby closed including the said battery, the release magnet c^3 and the switch c^{15} operated by the release relay c^4 . This circuit, when closed, results in the energizing of the release magnet c^3 and the consequent closing of the switch c^{16} controlled by said magnet. A circuit is then formed from the battery through the bus bar and the coil c^5 , through the trunk line conductor 3, through the private bank contact b^{11} , through the private wiper b^8 , and thence through the coil of the release relay b^6 , and through the private wiper b^7 of the side switch to ground and back to the battery. The release relay b^6 , when thus energized, closes the switch b^{14} and thereby completes a circuit from battery through the bus bar and the coil of the release magnet b^5 , and thence to ground and back to the battery. In this way the energizing of the permanently bridged coils d^2 and d^3 results in a series of operations, commencing at the connector and extending back over the trunk line connections to the first selector. The release magnets of the connector, second selector and first selector, when energized, effect a release of the three switches, through the medium of any suitable, known or approved devices. The release relays of the first and second selectors are preferably low wound, while the coils c^5 and d^6 are of, say, one hundred ohms resistance. The private magnet, however, may be of three hundred and fifty ohms resistance. In this way the resistance of the said private magnets is sufficient to prevent the energizing of any release relays which may be momentarily included in circuit therewith, as might be the case if a third subscriber should attempt to use the second selector E during conversation between the calling and called subscribers. The resistance of the coils c^5 and d^6 is sufficient to maintain the necessary guarding potential at the private bank contacts b^{11} and c^{11} . In other words, the resistance furnished by these coils, and interposed between the negative pole of the battery and said contacts, is much more than any resistance which may be included in the connections between the positive pole of the battery and the said private bank contacts. Consequently there is always a guarding potential of a positive character at the said private bank contacts.

It will be readily understood that the energizing of the different magnets in the connector, second selector and first selector occurs practically at the same time, all three switches being released practically as soon as the calling subscriber operates the switch a^1 . 70

During conversation between the subscribers there are no coils in series in the talking circuit, and there are no coils in bridge of the talking circuit at the calling side of the condensers, with the single exception of the coils d^2 and d^3 . Thus the efficiency of the talking currents is in no way interfered with, and at the same time ample and effective provision is made whereby the calling subscriber may release or restore the switches as soon as the conversation is terminated. The private wipers on the switch shafts of both the first and second selectors have the double function, so to speak, of establishing a guarding potential at the contacts of the private banks, and of closing one of the normally open switch points in the release circuits. The connector releases the second selector over a third or additional trunk line conductor, and the second selector releases the first selector over a third or additional trunk line conductor. The release magnet of the connector is used for releasing the connector and for closing a normally open switch point in the release circuit of the second selector. In a similar way the release magnet of the second selector is used for closing a normally open switch point in the release circuit of the first selector. The release relay, however, of the second selector controls a normally open switch point in the release magnet circuit of the second selector; but the release magnet of the second selector both controls a release circuit including a release relay, and is itself in turn controlled by another release relay. In this way the process of connecting up a calling subscriber with a called subscriber proceeds in one direction, while the operation of making a disconnection starts at the other end of the train of connections and proceeds in the opposite direction. 100 105 110 115

The talking circuit shown is, of course, normally open. The relays b^2 and b^3 are normally in bridge across conductors of said circuit, as are also the relays c and c^1 . The plurality of bridges thus provided are, however, cut off or opened up as soon as the talking circuit is closed, or rather as soon as the talking circuit is completed from the calling subscriber's station through to the trunk line leading to the connector. Evidently, and as previously explained, the talking circuit is at all times free from inductive resistance in the path of the talking currents between the transmitting and receiving ends of the circuit. And even when 120 125 130

the talking circuit is completed, and while the subscribers are talking, there are only three bridges across the circuit, to-wit, the bridge containing the coils d^2 and d^3 , the 5 bridge containing the coils d and d^1 , and the bridge b^2 , b^3 of the called subscriber's first selector. The bridge containing the coils d and d^1 can be omitted if such is desired.

10 As previously stated, Fig. 1 represents a connection in an exchange employing first selectors, second selectors and connectors. In such a system the numbers of the lines would comprise four digits and the exchange 15 would have a maximum capacity of ten thousand lines. If it is desired to provide an exchange of a larger capacity it is evident that all that is necessary is to insert additional selector switches between the second 20 selectors and connectors. By adding so-called third selectors the capacity of the exchange is increased to one hundred thousand. Fig. 2 represents a connection in such an exchange. The substation A, first selector B, second selector C and connector D are 25 the same as shown in Fig. 1 and are given the same reference numerals. The third selector G is in all respects the same as the second selector C. In such a system it is 30 evident that the release takes place in practically the same manner as the release in the system shown in Fig. 1, the only difference being that the release magnet d^5 of the connector operates to close the circuit of the release relay g^4 of the third selector G instead 35 of that of relay c^4 of the second selector C, and the circuit of said relay c^4 is closed by the release magnet g^3 of the third selector G instead of by the release magnet of the connector. 40

From the foregoing it will be seen that this system may readily be extended to any desired size by simply adding additional selectors similar to the selector C.

45 Wherever I use the expression "metallic circuit trunk line" I mean a trunk line in which there is a metallic circuit for talking purposes, in contra-distinction to a talking circuit in which but a single conductor is employed with a ground return; for example, the trunk line which extends between the first and second selectors I call a metallic circuit trunk line, even though a grounded third conductor is associated with this line, as it contains two conductors which compose a metallic talking circuit; likewise the trunk lines which extend from the second to the third selectors and to the connector, are all metallic circuit trunk lines, as these trunks contain a metallic talking circuit.

60 What I claim as my invention is:—

1. An automatic telephone system comprising a first "selector", a second "selector" and a "connector", a "release-circuit" for the first "selector", together with means for sup-

plying all necessary current, said second "selector" being provided with a "release-magnet" controlling a normally-open switch-point in the said "release-circuit".

2. An automatic telephone system comprising a first "selector", a second "selector" and a "connector", a "release-circuit" for the second "selector", a "release-circuit" for the first "selector", together with means for supplying all necessary current, the "connector" 70 having a "release-magnet" controlling a normally-open switch-point in the "release-circuit" of the second "selector", and the second "selector" having a "release-magnet" controlling a normally-open switch-point in 75 the "release-circuit" of the first "selector".

3. An automatic telephone system comprising a plurality of "selectors", trunk-line connection between said "selectors", said trunk-line connection including a pair of 85 main conductors, and an additional or third trunk-line conductor, a "connector" having trunk-line connection with the said "selectors", said "connector" trunk-line connection including a third or additional trunk-line 90 conductor, a "release-circuit" for the first "selector" including one of said additional trunk-line conductors, a "release-circuit" for the second "selector" including another of said additional trunk-line conductors, together with means for supplying all necessary current, said "connector" being provided with an electro-magnet adapted to control a normally-open switch-point in the "release-circuit" of the second "selector", 100 and the said second "selector" being provided with an electro-magnet controlling a normally-open switch-point in the "release-circuit" of the first "selector".

4. An automatic telephone system comprising a plurality of automatic step-by-step selective switching machines, each machine having a "release-circuit", the "release-circuit" of one machine being provided with a normally-open switch-point located 105 in another machine, the said other machine being provided with an electro-magnet controlling said switch-point, and with a relay controlling the said electro-magnet, a trunk talking circuit extending through all of said 110 switching machines, means for supplying all necessary current, and a trunk conductor included in each release circuit.

5. An automatic telephone system comprising a plurality of "selectors", a "connector", a "release circuit" for each "selector", the "connector" being provided with electro-magnetic means for controlling the "release-circuit" of a "selector", and each "selector" except the first one being provided 120 with electro-magnetic means for controlling the "release-circuit" of another "selector", together with means for supplying all necessary current.

6. An automatic telephone system com- 130

- prising a normally-open talking circuit, subscriber-operated means for closing said circuit for talking purposes, including a plurality of bridges normally connected across said circuit, and means for successively cutting off or opening said bridges when said circuit is closed, said circuit being at all times free from inductive resistance in the path of the voice currents.
10. 7. An automatic telephone system comprising a selector having release mechanism, a release-magnet adapted to operate said mechanism when energized and de-energized, a trunk-selecting switch mechanism provided with releasing means, a release circuit controlling said releasing means, and normally open contacts included in said release circuit and operated by said magnet.
15. 8. An automatic telephone system comprising a first-selector provided with releasing means, a release-circuit controlling said releasing means, a second-selector provided with release mechanism, an electro-magnet for operating said mechanism, normally open contacts included in said circuit and operated by said magnet, and a centralized source of switching current.
20. 9. In a telephone system, the combination of a switching machine provided with release mechanism, an electro-magnet for operating said mechanism, another machine provided with release mechanism, a release-magnet and a release-relay, a third machine provided with releasing means, a circuit for said relay controlled by said electro-magnet a circuit for said release-magnet controlled by said relay, a circuit for said releasing means controlled by said release-magnet, and a centralized source of switching current.
25. 10. In a telephone system, a connector and a plurality of selectors connected up in series and provided with release-magnets, a talking circuit, means for initiating a release of the connector over the talking circuit, and means independent of the talking circuit for completing the release from the connector back through the second and first selectors.
30. 11. In a telephone exchange system, the combination of a talking circuit, a series of bridges on the conductors of said circuit, means for cutting off a plurality of said bridges, and means for retaining one of said bridges during talking for releasing purposes.
35. 12. In a telephone exchange system, the combination of a talking circuit, a series of bridges on the conductors of said circuit, means for cutting off a plurality of said bridges, trunk release circuits, and means for retaining one of said bridges during talking to control said release circuits.
40. 13. In a telephone exchange system, the combination of telephone lines, automatic means for trunking calling lines in connec-
- tion with called lines, comprising a series of bridges across the conductors of any talking circuit provided between calling and called subscribers, means for cutting off a plurality of said bridges, releasing means for disconnecting between subscribers, and means for retaining one of said bridges to enable a subscriber on a talking circuit to control said releasing means.
45. 14. In a telephone exchange system, the combination of a talking circuit, a series of bridges on the conductors of said circuit, and automatic means for successively removing a plurality of said bridges.
50. 15. In a telephone exchange system, the combination of a talking circuit, a series of bridges on the conductors of said circuit, line relays in said bridges, circuits controlled by said relays, automatic means for cutting off a plurality of said bridges, means for retaining one of said bridges during talking, and releasing means controlled by the said retained bridge or bridges.
55. 16. In a telephone exchange system, the combination of a talking circuit, a series of bridges on the conductors of said circuit, electromagnets in said bridges, automatic means for cutting off a plurality of said bridges, and means for retaining one or more of said bridges during talking.
60. 17. In a telephone exchange system, the combination of a talking circuit, a plurality of selectors in said circuit, a connector in said circuit, the selectors and connector having bridges on the conductors of said circuit, automatic means for cutting off the bridges of the selectors, and means for retaining the bridge or bridges of the connector.
65. 18. In a telephone exchange system, the combination of selectors, trunk lines leading therefrom, means in said selectors for selecting idle trunk lines, other selectors at the ends of said trunk lines, other trunk lines leading from said other selectors, means in said other selectors for selecting idle trunk lines, each trunk line comprising a pair of voice-current conductors and a third or special conductor for purposes other than talking.
70. 19. In a telephone exchange system, the combination of a plurality of selectors, three-wire trunks for connecting said selectors together, and subscriber-controlled means ahead of the selectors for releasing the same over the third wire of said trunks.
75. 20. In a telephone system, a calling line and a called line, means including a plurality of automatic trunk selectors for extending connection from the calling line to the called line, a trunk-release circuit over which the second-selector releases the first-selector, and means ahead of the second selector for controlling the release of both selectors.

21. In a telephone system, a plurality of first-selectors and second selectors, each first selector adapted and operative to seize an idle trunk leading to a second-selector, means by which the second-selector is operative to release any first-selector over a conductor of said trunk, and means ahead of the second selector for controlling the release of both selectors.
- 10 22. In a telephone system, an open talking circuit, a plurality of bridges across said circuit, means controlled by said bridges for automatically and progressively establishing said circuit, means for cutting off a plurality of said bridges before reaching the called line, and means for releasing over trunk conductors by means of a bridge retained across said circuit for that purpose.
- 15 23. In an automatic telephone trunking system, means whereby idle trunks are automatically selected in accordance with the first and second digits of any called number, including a central station, a substation connected therewith through a metallic circuit line, a source of current, a selector controlling magnet at the central station for connection with said line, and an electrically operative device the operating circuit of which is controlled by said controlling magnet for causing disconnection of said controlling magnet from the circuit.
- 20 24. In a telephone trunking system, means whereby idle trunks are automatically selected in accordance with the first and second digits of any called number, including a metallic circuit line, a selector for said line, a controlling magnet for said selector normally bridged across the talking circuit of said line, a source of current connected between said magnet and ground, means at said substation for completing connection between said line and said third conductor for energizing said magnet, a side switch for said selector adapted to disconnect said
- 25 magnet from said line, a relay at the central office for controlling said side switch, and means at the substation for energizing said relay to cause the operation of said side switch to disconnect said first magnet from said line, substantially as described.
- 30 25. In an automatic telephone trunking system, means whereby idle trunks are automatically selected in accordance with the first and second digits of any called number, including a metallic circuit subscriber's line, a metallic circuit trunk line to which said subscriber's line is adapted to be extended, selecting switches for said subscriber's line and said trunk line, controlling magnets for each of said selecting switches normally connected respectively with said subscriber's and trunk lines, a side switch for said subscriber's selecting switch adapted to disconnect its controlling magnets from the subscriber's line, means for causing the selecting switch of said line to connect said line with said trunk, and to simultaneously disconnect said controlling magnets from said line, substantially as described.
- 35 26. In an automatic telephone trunking system, means whereby idle trunks are automatically selected in accordance with the first and second digits of any called number, including two subscribers' lines extending to a central office, a first selector for one of said lines, a trunk line, a second selector therefor, another trunk line, a third selector therefor, controlling magnets for each selector, a trunk line leading from said third selector, a connector, controlling magnets for said connector, means for causing the first selector to automatically select and connect with said first trunk line, means for causing said second selector to automatically select and connect with said second trunk line, means for causing said third selector to automatically select and connect with said third trunk line, means for connecting said third trunk line with the second subscriber's line, and means for automatically rendering the controlling magnets of said first and second selectors inoperative when said selectors have performed their selective function, substantially as described.
- 40 27. In a telephone trunking system, means whereby idle trunks are automatically selected in accordance with the first and second digits of any called number, including a pair of subscribers' lines, connected by trunk lines at a central office, automatic selecting devices for said subscribers' lines, and for each of said trunk lines, a pair of controlling magnets bridged across said metallic circuit line at one of said selecting devices, means under control of said magnets for causing all of said selecting devices to return to their normal position and break the connection between said subscribers' lines and said trunk lines, substantially as described.
- 45 28. In an automatic telephone trunking system, means whereby idle trunks are automatically selected in accordance with the first and second digits of any called number, including a subscriber's line, a selecting switch for said line at a central office, a trunk line to which said subscriber's line is extended by the movement of the selecting switch of said subscriber's line, a selecting switch for said trunk line, a pair of controlling magnets for each of said selecting switches adapted to control the selecting movements of said switches, the magnets at the selecting switch of said subscriber's line being in an open bridge across said subscriber's line during a connection between said line and said trunk, said magnets in the selecting switch of said trunk being connected in a closed bridge across said trunk during a connection with said line, and means associated with the selecting switch of said
- 50 55 60 65 70 75 80 85 90 95 100 105 110 115 120 125 130

line and controlled by the bridged magnets of the selecting switch of said trunk to cause the selecting switch of said line to assume its normal position, disconnecting said line from said trunk, substantially as described.

29. In an automatic telephone trunking system, means whereby idle trunks are automatically selected in accordance with the 10 first and second digits of any called number, including a built-up circuit between two subscribers' lines, selecting switches and trunk lines involved in building up said circuit, controlling magnets connected with said circuit at some of said selecting switches, other controlling magnets disconnected from said circuit at other of said selecting switches, and means at the switches having connected magnets for causing those switches having disconnected magnets to disconnect said built-up circuit, substantially as described.

30. In an automatic telephone trunking system, means whereby idle trunks are automatically selected in accordance with the 25 first and second digits of any called number, including a subscriber's line, a first selector therefor, selecting contacts for said first selector, a trunk line adapted to be connected to said subscriber's line by said first selector, a second selector for said trunk line, controlling magnets at said first and second selectors, means for energizing the magnets of said first selector to move said selecting contacts into engagement with said trunk 30 line, a switch actuated by said magnets during their selecting operation to disconnect said magnets from said line, a release magnet for said first selector, a separate conductor individual to said trunk line, and means controlled by the magnets of said second selector for causing the operation of the release magnet of said first selector over said 35 separate conductor, substantially as described.

31. An automatic telephone trunking system, means whereby idle trunks are automatically selected in accordance with the first and second digits of any called number, including a temporarily established talking 50 circuit, a selector relay bridge temporarily disconnected or cut off from the said circuit, and a connector relay bridge retained across the said circuit for releasing purposes, together with selector and connector releasing means controlled by the said connector relay bridge.

32. In a telephone exchange trunking system, means whereby idle trunks are automatically selected in accordance with the 60 first and second digits of any called number, including a talking circuit, a plurality of bridges on the conductors of said circuit automatic means for reducing the number of bridges, releasing means for disconnecting subscribers, and means for retaining one of

said bridges during talking to control the said releasing means.

33. In a telephone exchange trunking system, means whereby idle trunks are automatically selected in accordance with the 70 first and second digits of any called number, including telephone lines, automatic means for trunking a calling line into connection with a called line to form a talking circuit, a bridge over the conductors of said circuit, 75 and automatic means for cutting off or opening up said bridge during talking.

34. In an automatic telephone system, a metallic circuit subscriber's line, a first selector therefor, a trunk line to which 80 said first selector is adapted to extend said subscriber's line, a second selector for said trunk line, a second trunk line to which said second selector is adapted to extend said first trunk line, a third selector for said second trunk line, operating magnets for each selector for controlling said selectors in extending the circuits of their respective lines, and a switch for said first and second selectors under control of said magnets for disconnecting said magnets from said lines after they have performed their operating 85 functions, substantially as described.

35. In an automatic telephone system, a metallic circuit subscriber's line, a first selector therefor, a trunk line to which said first selector is adapted to extend said subscriber's line, a second selector for said trunk line, a second trunk line to which said second selector is adapted to extend said first trunk line, a third selector for said second trunk line, operating magnets for each selector for controlling said selectors in extending the circuits of their respective lines, a switch for said first and second selectors under control of said magnets for disconnecting said magnets from said lines after they have performed their operating functions, and means under control of said 95 third selector for causing said first and second selectors to discontinue the extended connections between said subscriber's line and said trunk lines, substantially as described.

36. In a telephone system, two subscribers' telephone lines, a first selector for one of said lines, a connector in which the other said line terminates, a second and a third selector, two trunk lines terminating respectively in said second and third selectors, a third trunk line terminating in said connector, means under the control of said first subscriber's line for causing said first selector to automatically select and connect with the trunk line terminating in said second selector, for causing said second selector to automatically select and connect with the trunk line terminating in said third selector, for causing said third selector to automatically select and connect with said trunk line 100 105 110 115 120 125 130

extending to said connector, and for causing said connector to select and connect with said second subscriber's line, controlling magnets for said selectors, and automatic means in connection with said first and second selectors for opening the circuit of the controlling magnets of said selectors, substantially as described.

37. In a telephone system, two subscribers' 10 telephone lines, a selecting switch for one of said telephone lines, waiting connection terminals for the other of said telephone lines, a plurality of trunk lines, a line selecting switch for one of said trunk lines, 15 trunk selecting switches for the other trunk lines, electromagnetic controlling mechanisms under the control of said first subscriber for operating said selecting switches to successively select and connect said trunk 20 connecting switches serially with said first line, electromagnetic means for causing the lines selecting switch of the last selected trunk line to select and connect with the waiting terminals of said second subscriber's 25 line, electromagnetic switch mechanisms for controlling the circuit of the electromagnetic selector mechanisms, a circuit for said electromagnetic switch mechanisms, said circuit being controlled by said electromagnetic 30 controlling mechanisms, and means for restoring all of said selecting switches to their normal positions, substantially as described.

38. In an automatic telephone system, a 35 telephone line, a selecting switch for said line at a central station, a trunk line to which said line is extended by said selecting switch, a selecting switch for said trunk line, controlling magnets for each of said selecting switches, said magnets of the switch 40 of said line being disconnected from said line during the connection of said line with said trunk, said magnets of the switch of said trunk being operatively connected with said trunk during said connection, and 45 means associated with said selective switch of said line controlled by the magnets of said trunk to cause the disconnection of said line from said trunk, substantially as described.

50 39. In an automatic telephone system, a subscriber's line, a selecting switch for said line at a central office, a trunk line to which said subscriber's line is extended by the selecting switch of said subscriber's line, a selecting switch for said trunk line, a pair of 55 controlling magnets for each of said selecting switches, the magnets at the selecting switch of said subscriber's line being in an open bridge across said subscriber's line during a connection between said line and said trunk, said magnets in the selecting switch of said trunk being connected in a closed bridge across said trunk during a connection with said line, and means associated with the 60 65 selecting switch of said line and controlled

by the bridged magnets of the selecting switch of said trunk to cause the disconnection of said line from said trunk, substantially as described.

40. In an automatic telephone system, a 70 subscriber's line, a trunk line, selecting switches for said subscriber's line and for said trunk line, a pair of controlling magnets for the selecting switch of said subscriber's line bridged across said subscriber's line, means for energizing said magnets to cause said selecting switch to select and connect with said trunk line, automatic means for disconnecting said controlling magnets from said line when said selection 75 and connection is accomplished, a pair of controlling magnets bridged across said trunk line, means under the control of the subscriber's line for energizing said magnets, and means controlled by the simultaneous operation of said latter magnets to cause the selecting switch of said line to release said trunk, substantially as described.

41. In an automatic telephone system, two subscribers' lines connected for conversation 90 by trunk lines and selecting switches, said trunk lines and selective switches controlling magnets bridged across the talking circuit between said lines at some of said selecting switches, release magnets for all of 95 said selecting switches, means for energizing said bridged controlling magnets to operate the disconnect magnets of their own and of the other selecting switches involved in making the connection, substantially as 100 described.

42. In an automatic telephone system, a subscriber's line, a first selector therefor, selecting contacts for said first selector, a trunk line adapted to be connected to said subscriber's line by said first selector, a second selector for said trunk line, controlling magnets at said first and second selectors, means for energizing the magnets of said first selector to move said selecting contacts 110 into engagement with said trunk line, a switch actuated by said magnets during their selecting operation to disconnect said magnets from said line, a release magnet for said first selector, and means controlled 115 by the bridged magnets of said second selector to operate the release magnet of said first selector, substantially as described.

43. In a telephone system, a metallic circuit line, a selector for said line, a controlling magnet for said selector normally bridged across the talking circuit of said line, a third conductor, a source of current connected between said magnet and said third conductor, means at said substation for completing connection between said line and said third conductor for energizing said magnet, a side switch for said selector adapted to disconnect said magnet from said line, a relay at the central office for controlling 120 125 130

said side switch, and means at the substation for energizing said relay to cause the operation of said side switch to disconnect said first magnet from said line, substantially as described.

44. In an automatic telephone system, a metallic circuit subscriber's line, a metallic circuit trunk line to which said subscriber's line is adapted to be extended, selecting switches for said subscriber's line and said trunk line, controlling magnets for each of said selecting switches normally connected respectively with said subscriber's and trunk lines, a side switch for said subscriber's selecting switch adapted to disconnect its controlling magnets from the subscriber's line, means for causing the selecting switch of said line to connect said line with said trunk, and to simultaneously disconnect said controlling magnets from said line, substantially as described.

45. In an automatic telephone system, two subscribers' lines extending to a central office, a first selector for one of said lines, a trunk line, a second selector therefor, another trunk line, a third selector therefor, controlling magnets for each selector, a trunk line leading from said third selector, a connector, controlling magnets for said connector, means for causing the first selector to automatically select and connect with said first trunk line, means for causing said second selector to automatically select and connect with said second trunk line, means for causing said third selector to automatically select and connect with said third trunk line, means for causing the connector to automatically connect said third trunk line with the second subscriber's line, and means for automatically rendering the controlling magnets of said first and second selectors inoperative when said selectors have performed their selective function, substantially as described.

46. In a telephone system, a pair of subscribers' lines including a metallic circuit connected by trunk lines at a central office, automatic selecting devices for said subscribers' lines, and for each of said trunk lines, a pair of controlling magnets bridged across said metallic circuit line at one of said selecting devices, and means under control of said magnets for causing all of said selecting devices to return to their normal position and break the connection between said subscribers' lines and said trunk lines, substantially as described.

47. In an automatic telephone system, a subscriber's line, a selecting switch for said line at a central office, a trunk line to which said subscriber's line is extended by the movement of the selecting switch of said subscriber's line, a selecting switch for said trunk line, a pair of controlling magnets for each of said selecting switches adapted to control the selecting movements of said

switches, the magnets at the selecting switch of said subscriber's line being in an open bridge across said subscriber's line during a connection between said line and said trunk, said magnets in the selecting switch of said trunk being connected in a closed bridge across said trunk during a connection with said line, and means associated with the selecting switch of said line and controlled by the bridged magnets of the selecting switch of said trunk to cause the selecting switch of said line to assume its normal position, disconnecting said line from said trunk, substantially as described. 70

48. In an automatic telephone system, a built-up circuit between two subscribers' lines, selecting switches and trunk lines involved in building up said circuit, controlling magnets connected with said circuit at one of said selecting switches, other controlling magnets disconnected from said circuit at other of said selecting switches, and means at the switch having connected magnets for causing those switches having disconnected magnets to disconnect said built-up circuit, substantially as described. 80

49. In an automatic telephone system, a subscriber's line, a first selector therefor, selecting contacts for said first selector, a trunk line adapted to be connected to said subscriber's line by said first selector, a second selector for said trunk line, controlling magnets at said first and second selectors, means for energizing the magnets of said first selector to move said selecting contacts into engagement with said trunk line, a switch actuated by said magnets during their selecting operation to disconnect said magnets from said line, a release magnet for said first selector, a separate conductor individual to said trunk line, and means controlled by the magnets of said second selector for causing the operation of the release magnet of said first selector over said separate conductor, substantially as described. 90

50. An automatic telephone system comprising a temporarily established talking circuit, a selector relay bridge temporarily disconnected or cut off from the said circuit, and a connector relay bridge retained across the said circuit for releasing purposes, together with selector and connector releasing means controlled by the said connector relay bridge. 105

51. In an automatic telephone system, a central station, a substation connected therewith through a metallic circuit line, a source of current, a selector controlling magnet at the central station for connection with said line, an electrically operative device the operating circuit of which is controlled by said controlling magnet for causing disconnection of said controlling magnet from the circuit, a set of selector line wipers opera- 110

tive in accordance with an intermediate digit of the called number, and a set of connector line wipers operative in accordance with two digits of the called number to find the called line.

52. In a telephone system, a metallic circuit line, a selector for said line, a controlling magnet for said selector normally bridged across the talking circuit of said line, a third conductor, a source of current connected between said magnet and said third conductor, means at said substation for completing connection between said line and said third conductor for energizing said magnet, a side switch for said selector adapted to disconnect said magnet from said line, a relay at the central office for controlling said side switch, means controlled at the substation for energizing said relay to cause the operation of said side switch to disconnect said first magnet from said line, a set of selector line wipers operative in accordance with an intermediate digit of the called number, and a set of connector line wipers operative in accordance with two digits of the called number to find the called line, substantially as described.

53. An automatic telephone system comprising a temporarily established talking circuit, a selector relay bridge temporarily disconnected or cut off from the said circuit, a connector relay bridge retained across the said circuit for releasing purposes, together with selector and connector releasing means controlled by the said connector relay bridge, a set of selector line wipers operative in accordance with an intermediate digit of the called number, and a set of connector line wipers operative in accordance with two digits of the called number to find the called line.

54. In a telephone exchange system, the combination of a talking circuit, a plurality of bridges on the conductors of said circuit, automatic means for reducing the number of bridges, releasing means for disconnecting between subscribers, means for retaining one of said bridges during talking to control the said releasing means, a set of selector line wipers operative in accordance with an intermediate digit of the called number, and a set of connector line wipers operative in accordance with two digits of the called number to find the called line.

55. In a telephone exchange system, the combination of telephone lines, automatic means for trunking a calling line into connection with a called line to form a talking circuit, a bridge over the conductors of said circuit, automatic means for cutting off or opening up said bridge during talking, a set of selector line wipers operative in accordance with an intermediate digit of the called number, and a set of connector line wipers operative in accordance with two

digits of the called number to find the called line.

56. In an automatic telephone system, a subscriber's line, a metallic circuit trunk line, a selector serving to connect said subscriber's line with said trunk line, controlling magnets for said selector, switches operated by said controlling magnets to open the circuit of said magnets upon the completion of a selection, and electromagnet mechanism controlled over the line circuit to actuate said selector to disconnect said subscriber's line from said trunk line.

57. In an automatic telephone system, a subscriber's line, a selecting switch therefor, a trunk line, controlling magnets normally bridged across the subscriber's line for causing said switch to select and connect with said trunk line, means for automatically disconnecting said controlling magnets from said line after their operation, a source of current adapted to supply current over said trunk line to said subscriber's line, and means operated by current from said source over said trunk line to cause said switch to disconnect said subscriber's line from said trunk line, substantially as described.

58. In an automatic telephone system, a metallic circuit line, a substation in said line, a selecting switch for said line, controlling magnets for said switch, a disconnect magnet for said switch, a metallic circuit trunk line, means at said substation for causing the selecting switch of said line to select and connect with said trunk line, means for automatically disconnecting said controlling magnets from said line after such selection and connection, and means operated over the limbs of said trunk line for closing the circuit of said disconnect magnet to cause said selecting switch to release said trunk, substantially as described.

59. In an automatic telephone system, a metallic circuit line, a substation and a selecting switch for said line, controlling magnets for said switch normally in operative relation with said line, a metallic circuit trunk line, means at said substation for causing its selecting switch to select and connect with said trunk line, means for automatically placing said controlling magnets in inoperative relation with said line after such selection and connection, relays connected with the limbs of said trunk, and means controlled by said relays for causing said selecting switch to disconnect said line from said trunk line, substantially as described.

60. In an automatic telephone system, a subscriber's line, a metallic circuit trunk line, a selector serving to connect said subscriber's line with said trunk line, controlling magnets for said selector, switches operated by said controlling magnets to open the circuit of said magnets upon the completion of a selection, and electromagnet mechanism in-

cluding a third conductor trunk-release circuit controlled over the line circuit to actuate said selector to disconnect said subscriber's line from said trunk line.

6. 61. In an automatic telephone system, a subscriber's line, a selecting switch therefor, a trunk line, controlling magnets normally bridged across the subscriber's line for causing said switch to select and connect with said trunk line, means for automatically disconnecting said controlling magnets from said line after their operation, a source of current adapted to supply current over said trunk line to said subscriber's line, and means including a third conductor trunk-release circuit operated by current from said source over said trunk line to cause said switch to disconnect said subscriber's line from said trunk line, substantially as described.
- 10 62. In an automatic telephone system, a metallic circuit line, a substation in said line, a selecting switch for said line, controlling magnets for said switch, a disconnect magnet for said switch, a metallic circuit trunk line, means at said substation for causing the selecting switch of said line to select and connect with said trunk line, means for automatically disconnecting said controlling magnets from said line after such selection and connection, and means including a third conductor trunk-release circuit operated over the limbs of said trunk line for closing the circuit of said disconnect magnet to cause said selecting switch to release said trunk, substantially as described.
- 15 63. In an automatic telephone system, a metallic circuit line, a substation and a selecting switch for said line, controlling magnets for said switch normally in operative relation with said line, a metallic circuit trunk line, means at said substation for causing its selecting switch to select and connect with said trunk line, means for automatically placing said controlling magnets in inoperative relation with said line after such selection and connection, relays connected with the limbs of said trunk, and means including a third conductor trunk-release circuit controlled by said relays for causing said selecting switch to disconnect said line from said trunk line, substantially as described.
- 20 64. In a telephone system, a pair of subscribers' lines including a metallic circuit connected by trunk lines at a central office, automatic selecting devices for said subscribers' lines, and for each of said trunk lines, a pair of controlling magnets bridged across said metallic circuit line at one of said selecting devices, and means under control of said magnets for causing all of said selecting devices to return to their normal position and break the connection between said subscribers' lines and said trunk lines, one of said selecting devices having a wiper
- 25 shaft with a third wiper thereon, said means including a release circuit through the said third wiper, and a busy test circuit including the same wiper, substantially as described.
- 30 65. In an automatic telephone system, a subscriber's line, a selecting switch for said line at a central office, said switch having a wiper shaft with a third wiper thereon, a trunk line to which said subscriber's line is extended by the movement of the selecting switch of said subscriber's line, a selecting switch for said trunk line, a pair of controlling magnets for each of said selecting switches adapted to control the selecting movements of said switches, the magnets at the selecting switch of said subscriber's line being in an open bridge across said subscriber's line during a connection between said line and said trunk, said magnets in the selecting switch of said trunk being connected in a closed bridge across said trunk during a connection with said line, and means associated with the selecting switch of said line, including a release circuit through the said third wiper, and controlled by the bridged magnets of the selecting switch of said trunk to cause the selecting switch of said line to assume its normal position, disconnecting said line from said trunk, and a busy test circuit including the same wiper, substantially as described.
- 35 66. In an automatic telephone system, a built-up circuit between two subscribers' lines, selecting switches and trunk lines involved in building up said circuit, controlling magnets connected with said circuit at one of said selecting switches, other controlling magnets disconnected from said circuit at other of said selecting switches, said other switches each having a wiper shaft with a third wiper thereon, means including release circuits through the said third wipers, which circuits are at the switch having connected magnets for causing those switches having disconnected magnets to disconnect said built-up circuit, and busy test circuits including the third wipers, substantially as described.
- 40 67. In an automatic telephone system, a subscriber's line, a first selector therefor, selecting contacts for said first selector, a trunk line adapted to be connected to said subscriber's line by said first selector, a second selector for said trunk line, controlling magnets at said first and second selectors, means for energizing the magnets of said first selector to move said selecting contacts into engagement with said trunk line, a switch actuated by said magnets during their selecting operation to disconnect said magnets from said line, a release magnet for said first selector, a separate conductor individual to said trunk line, said first selector having a wiper shaft with a third

wiper thereon, means including a release circuit through said third wiper, said circuit controlled by the magnets of said second selector, for causing the operation of the release magnet of said first selector over said separate conductor, and a busy test circuit including the third wiper, substantially as described.

68. An automatic telephone system comprising a temporarily established talking circuit, a selector relay bridge temporarily disconnected or cut off from the said circuit, a selector wiper controlled by said bridge, a connector relay bridge retained across the said circuit for releasing purposes, together with selector and connector releasing means, including a release circuit through said wiper, controlled by the said connector relay bridge, and a busy test circuit including said wiper.

69. In a telephone exchange system, the combination of a talking circuit, a plurality of bridges on the conductors of said circuit, automatic means for reducing the number 25 of bridges during talking, a shaft having a wiper associated with and allotted to one of said bridges, releasing means for disconnecting between subscribers, means for retaining one of said bridges to control the 30 said releasing means, and a busy test circuit including said wiper.

70. In a telephone system, a pair of subscribers' lines including a metallic circuit connected by trunk lines at a central office, 35 automatic selecting devices for said subscribers' lines, and for each of said trunk lines, a pair of controlling magnets bridged across said metallic circuit line at one of said selecting devices, and means under control of said magnets for causing all of said 40 selecting devices to return to their normal positions and break the connection between said subscribers' lines and said trunk lines, one of said selecting devices having a shaft 45 with a plurality of wipers thereon, and said means including a release circuit through one of said wipers, substantially as described.

71. In an automatic telephone system, a 50 subscriber's line, a selecting switch for said line at a central office, said switch having a shaft with a plurality of wipers, a trunk line to which said subscriber's line is extended by the movement of the selecting switch of said subscriber's line, a selecting switch for said trunk line, a pair of controlling magnets for each of said selecting switches adapted to control the selecting 55 movements of said switches, the magnets at the selecting switch of said subscriber's line being in an open bridge across said subscriber's line during a connection between said line and said trunk, said magnets in the selecting switch of said trunk being connected in a closed bridge across said trunk 60

during a connection with said line, and means associated with the selecting switch of said line, including a release circuit through one of said wipers, and controlled by the bridged magnets of the selecting switch of said trunk to cause the selecting switch of said line to assume its normal position, disconnecting said line from said trunk, substantially as described.

72. In an automatic telephone system, a built-up circuit between two subscribers' lines, selecting switches and trunk lines involved in building up said circuit, controlling magnets connected with said circuit at one of said selecting switches, other controlling magnets disconnected from said circuit at other of said selecting switches, said other switches each having a shaft with a plurality of wipers, and means including release circuits through some of said wipers, which circuits are controlled at the switch having connected magnets, for causing those switches having disconnected magnets to disconnect said built-up circuit, substantially as described.

73. In an automatic telephone system, a subscriber's line, a first selector therefor, selecting contacts for said first selector, a trunk line adapted to be connected to said subscriber's line by said first selector, a second selector for said trunk line, controlling magnets at said first and second selectors, means for energizing the magnets of said first selector to move said selecting contacts into engagement with said trunk line, a switch actuated by said magnets during their selecting operation to disconnect said magnets from said line, a release magnet for said first selector, a separate conductor individual to said trunk line, said first selector having a shaft with a plurality of wipers, and means including a release circuit through one of said wipers, said circuit controlled by the magnets of said second selector, for causing the operation of the release magnet of said first selector over said separate conductor, substantially as described.

74. An automatic telephone system comprising a temporarily established talking circuit, a selector relay bridge temporarily disconnected or cut off from the said circuit, a selector wiper controlled by said bridge, and a connector relay bridge retained across the said circuit for releasing purposes, together with selector and connector releasing means, including a release circuit through said wiper, controlled by the said connector relay bridge.

75. In a telephone exchange system, the combination of a talking circuit, a plurality of bridges on the conductors of said circuit, automatic means for reducing the number of bridges during talking, a shaft having a wiper associated with and allotted to one of said bridges, releasing means for disconnecting

- necting between subscribers, said releasing means including a circuit through said wiper, which wiper is excluded from the talking circuit, and means for retaining one of said bridges to control the said releasing means.
76. In a telephone exchange system, the combination of a talking circuit, a plurality of bridges on the conductors of said circuit, 10 said bridges containing electromagnetic devices for controlling the establishment of the talking circuit, automatic means for reducing the number of bridges during talking, releasing means for disconnecting between subscribers, one of said bridges remaining to control the said releasing means.
77. In a telephone exchange system provided with selector switches of various classes at the exchange, including connector 15 switches adapted to co-operate with calling devices at the substations in establishing desired connections, the combination with a subscriber's line, of a first selector switch adapted to be operated under substation control, second selector switches, multiple terminals of said second selector switches, and wipers included in said first selector switch adapted to engage said terminals, a part of 20 said wipers being for conversational use, a test wiper enabling said first selector to select and isolate an idle second selector, means for causing a flow of current over said wiper when disconnection is desired, and release mechanism at the exchange operated 25 responsive to said flow.
78. A telephone system including a pair of connected subscribers' lines, a plurality of selective switches at the exchange connecting said lines, talking contacts included in said 30 switches through which the conversational circuit extends, contacts included in some of said switches not forming part of the conversational circuit with means controlled by said contacts for preventing intrusion upon 35 the connection, a relay at the exchange controllable responsive to circuit changes produced at the calling substation, and means controlled by said relay for altering the connections of said last-mentioned contacts to 40 release the switches.
79. A telephone system including a telephone line, a selective switch at the exchange connected with said line, a second selective switch connected with said first switch, contacts of said switches forming 45 part of a talking circuit, an additional contact piece for said first switch in connection with a contact of said second switch serving to protect the talking circuit from intrusion, means for altering the electrical condition 50 of said contact piece when disconnection is desired, and release mechanism for restoring a selective switch responsive to said altered 55 electrical condition.
80. A telephone system including a tele-
- phone line, a selective switch at the exchange connected with said line, a second selective switch connected with said first switch, contacts of said switches forming part of a talking circuit, an additional contact piece 70 for said first switch in connection with a contact of said second switch serving to protect the talking circuit from intrusion, a release relay, means responsive to a switch at the substation of said line for altering the 75 operative condition of said relay when disconnection is desired, switching mechanism controlled by said relay for affecting the electrical condition of said contact piece on alteration of said operative condition as described, and release apparatus responsive to the electrical condition of said contact piece for restoring a selective switch.
81. A telephone system including telephone lines, interconnecting link-circuits 85 and a "selector" switch for extending the talking circuit of a calling line to an idle link-circuit, said "selector" switch including a test contact for use in selecting the idle link-circuit, and means for restoring said switch to normal including a circuit extending through said testing contact.
82. A telephone system including telephone lines, interconnecting link-circuits, a plurality of interconnecting automatic 90 switch mechanisms for uniting calling and called lines by link-circuits into a talking circuit, testing contacts associated with certain of said switch mechanisms for use in determining the link-circuits to be included 95 in said talking circuit, means for releasing one of said switch mechanisms, a circuit including a testing contact, and means operated by said releasing means over said circuit to release another of said switch mechanisms.
83. A telephone system including telephone lines, interconnecting link-circuits, a plurality of selective switch mechanisms for uniting a calling and a called line by link-circuits into a talking circuit, a private 100 contact associated with one of said switch mechanisms, a connection device for contact therewith to place a busy potential upon said contact to protect the talking circuit from 105 intrusion, a release circuit for one of said switch mechanisms including said private contact, and apparatus for altering the potential of said private contact when disconnection is desired to render said release circuit effective.
84. A telephone system including telephone lines, interconnecting link-circuits, "selector" and "connector" switches for uniting calling and called lines by certain of 110 said link-circuits into a talking circuit, said "selector" and "connector" switches being provided with testing contacts for use in determining the talking circuit, and means for releasing said "selector" switch including a 115
- 120
- 125
- 130

circuit through its testing contact in response to the release of said "connector" switch, and means for releasing the latter.

85. A telephone system including a telephone line, a selective switch at the exchange connected with said line, a second selective switch connected with said first switch, contacts of said switches forming part of a talking circuit, an additional contact piece for said first switch in connection with a contact of said second switch serving to protect the talking circuit from intrusion, a release relay, means for altering the operative condition of said relay when disconnection is desired, and release mechanism responsive to an altered electrical condition of said contact piece produced responsive to said relay for restoring a selective switch.

86. An automatic telephone system comprising a first selector, a second selector and a connector, a release-circuit for the first selector, together with means for supplying all necessary current, said second selector being provided with a release-magnet directly controlling the release and also controlling a normally-open switch point in said release-circuit.

87. In a telephone system, an automatic switch, a pair of line wipers, a third wiper therefor, a side switch having a plurality of positions, a relay, means for connecting said wiper to ground through said relay when the said side switch passes to third position, and a release magnet for controlling the release of said switch, the circuit of said release magnet being controlled by the first mentioned relay.

88. In a telephone system, subscribers' lines divided into groups, an automatic switch having motion in one plane to select groups, and motion in a plane at right angles thereto to find a line in the selected group, a pair of line wipers, a third wiper therefor, a side switch having a plurality of positions, a relay, means for connecting said third wiper to ground through said relay when said side switch passes to third position, and a release magnet for controlling the release of said switch, the circuit of said release magnet being controlled by said first mentioned relay.

89. A telephone system comprising a selector provided with a side switch, a release relay for releasing said selector while the said switch is in first or second position, and a release relay for releasing the said selector when the said switch is in third position.

90. A telephone system comprising automatic trunk selectors, automatic connectors provided with means having vertical motion from one operative level to another to select groups or divisions of the exchange, and rotary motion in any selected level to connect with a line therein, trunk release

circuits for the selectors controlled by the connectors, a calling device at each substation, and a source of operating current, said connectors each provided with one or more permanently bridged line relays permanently connected with said source of current.

91. In a telephone system employing bridging line relays, automatic trunk selectors having provisions for automatically reducing the number of bridges across the talking circuit during the establishment thereof, automatic connectors, trunk release circuits for the selectors controlled by the connectors, and a source of operating current, said connectors each provided with one or more permanently bridged line relays each permanently connected with said source of current.

92. In a telephone exchange system substantially as disclosed, the combination of a selector having release mechanism, the connector provided with a pair of line relays controllable over any calling subscriber's line to extend a connection to a called telephone line, said connector having release mechanism, there being a trunk release circuit extending between the selector and the connector for controlling the release of the connection, said release circuit having a plurality of normally open switch points, said relays being retained under the control of the calling subscriber for changing the condition of one of said switch points while the called telephone is closed across the connection for talking, a subscriber's impulse transmitter or calling device for transmitting to the exchange or central station the electrical impulses representing the number of any called subscriber.

93. In a telephone exchange system substantially as disclosed, the combination of a selector having release mechanism, a connector provided with a pair of line relays controllable over any calling subscriber's line to extend a connection to a called telephone line, said connector having release mechanism, and there being a trunk release circuit extending between the selector and the connector for controlling the release of the connection, said release circuit having a plurality of normally open switch points, the condition of one of the switch points subject to be changed by the calling subscriber while the called telephone is closed across the connection for talking, and subscribers' impulse transmitters or calling devices for transmitting to the exchange or central station the electrical impulses representing the number of any called subscriber.

94. An automatic telephone system comprising a battery, a trunk-line terminating in contacts, said contacts having a suitable number of multiples, an additional contact and a suitable number of multiples thereof, an automatic switch provided with means

for engaging said trunk-line contacts, and provided also with means for connecting one pole of said battery with said additional contacts for the purpose of preventing seizure by other parties of the said trunk-line when in use, and a release circuit for said switch including said additional contacts.

95. An automatic telephone system comprising an automatic switch provided with a guarding potential circuit and also with a releasing circuit, and having a switch-contact included in both of said circuits, and means for closing said releasing circuit to disconnect two connected subscribers.

15 96. An automatic telephone system comprising a subscriber's line, a selector-switch individual to said line, a trunk-line terminating in the contacts of said switch, and a connector-switch permanently connected 20 with the other end of said trunk-line, together with means including an additional trunk-line conductor for releasing the said selector switch, the releasing circuit being provided with a normally open switch-point 25 controlled by an element of the said connector-switch.

97. An automatic telephone system comprising switching apparatus including a private bank-contact, a normally open switch connected with said private bank-contact, a battery having one pole connected with said normally open switch, means for operating said switch, said normally open connection between the battery and said private bank-contact including a suitable resistance, the other pole of said battery being grounded, a private wiper adapted to engage said contact, and means for grounding said wiper when the switching apparatus is in use, the normally open connection between said wiper and ground including a relay-coil of less resistance than the said resistance in the normally open connection between the battery and the said contact, together with one or 45 more multiples of said contact.

98. An automatic telephone system comprising a trunk-line, a selector-switch adapted to make connection with one end of said trunk-line, said selector-switch having a release magnet and a release relay, another switch connected with the other end of said trunk-line, said other switch having a release magnet and a private magnet, means for furnishing all necessary current, and a release circuit for effecting the release of said selector-switch, said release circuit having a normally open switch-point controlled by the release magnet of said other switch, and having two other normally open switch-points controlled by said selector switch, the said release relay controlling the operation of the release magnet of the selector switch, and the private magnet of the said other switch controlling the said release magnet 65 thereof.

99. An automatic telephone system comprising a normally open talking circuit, a bridge normally connected across said circuit, means for cutting off or opening said bridge, said circuit being at all times free 70 from inductive resistance in the path of the voice currents, and a trunk-release circuit extending parallel with an intermediate portion of said circuit and controlled at the end thereof toward the calling subscriber. 75

100. An automatic telephone system comprising an automatic trunk-selecting switch mechanism provided with releasing means, a connector-switch provided with releasing means including a release-magnet, and a release circuit for operating the releasing means of the trunk-selecting switch mechanism, said circuit being controlled by the said release-magnet of the connector. 80

101. In a telephone system, a switching 85 machine, another switching machine, a release circuit connecting said switches, a source of switching current, other switches, and means for supplying a guarding potential from one pole of said battery to said other switches over a portion of said release circuit.

102. In a telephone system, a movable switch-contact, a normally open release circuit including said contact, means for closing said release circuit to disconnect two connected subscribers, and a normally-open busy-circuit which also includes said contact. 95

103. An automatic telephone system comprising switch-release mechanism, a release-magnet for operating said mechanism, a swinging switch-wiper, normally-open switch-contacts operated by the energizing and deenergizing of said release-magnet, a 105 trunk-line-conductor, and a normally-open circuit including said swinging switch-wiper and normally-open contacts.

104. An automatic telephone system comprising a switching machine having electrically-propelled and step-by-step switching mechanism, and having a pair of line-relays for controlling said mechanism, and another switching machine having release mechanism controlled by a release-relay, together with a release-circuit between switches including said relay, and means whereby the closing of said circuit to energize the said relay and thereby operate its release mechanism is accomplished by the simultaneous energizing 110 of said line-relays. 115

105. An automatic telephone system comprising a first-selector provided with a release-relay, a second-selector provided with a pair of line-relays, a battery for furnishing the current necessary for operating said selectors, and an energizing circuit for said release-relay controlled conjointly by said line-relays. 125

106. An automatic telephone system com- 130

prising a selector provided with a release-relay, a connector provided with a pair of line-relays, means for supplying the necessary current, and an energizing circuit for 5 said release-relay, controlled conjointly by said line-relays.

107. In an automatic telephone system, a metallic circuit subscriber's line, a metallic circuit trunk line to which said subscriber's 10 line is adapted to be extended, selecting switches for said subscriber's line and said trunk line, controlling magnets for each of said selecting switches connected respectively with said subscriber's and trunk lines, and 15 means for causing the selecting switch of said line to connect said line with said trunk, and to simultaneously disconnect said controlling magnet from said line, substantially as described.
108. The combination with a telephone 20 station, a pair of wires leading from the station to a central office, and a pair of wipers located at the central office and normally dis-

connected from said wires, of a series of 25 trunk connections, magnets operable by impulses sent over said wires to bring about a movement of said wipers to select a non-busy trunk connection, and means by which upon said wipers finding a non-busy trunk connection non-inductive connections will be 30 automatically completed from said station to said wipers.

109. The combination with a telephone station, a pair of wires leading from the station to a central office, and a pair of wipers 35 at the central office and normally disconnected from said wires, of a series of trunk lines, means for moving said wipers so as to select a non-busy trunk line, and means by which upon said wipers finding a non-busy trunk 40 line non-inductive connections will be automatically completed between said stations and said wipers.

Signed by me at Chicago, Cook County, Illinois, this 9th day of January, 1905.

ALEXANDER E. KEITH.
